UNITED STATES PATENT OFFICE.

GEORGE F. McCHEY, OF PROVIDENCE, RHODE ISLAND, ASSIGNOR TO J. M. BRAIDER, INC., OF EAST PROVIDENCE, RHODE ISLAND, A CORPORATION OF RHODE ISLAND.

BRAIDING MACHINE.

Application filed May 21, 1924. Serial No. 714,806.

To all whom it may concern:

Be it known that I, GEORGE F. McCHEY, a citizen of the United States, residing at Providence, in the county of Providence and State of Rhode Island, have invented certain new and useful Improvements in Braiding Machines, of which the following is a specification.

This invention relates to braiding machines of the class provided with oscillating carriers, and has for its object to provide in such a machine spaced-apart upper and lower raceways and means located intermediate these raceways for driving the carriers through the raceways whereby the upper portion of the carrier is caused to oscillate to compensate in a large measure for the in-and-out movements of the carrier relatively to the braiding center, causing its yarn delivering eye to take a course more nearly in a true circle about the braiding point and so materially reduce the action of the usual yarn take-up in the carrier.

A further object of this invention is the provision of a set of driving gears for the carrier, each being slotted to engage a portion of the carrier to advance it through the raceway, said gears being provided with teeth which are staggered and these teeth being arranged to provide entrance guides for the opposite side walls of these driving slots to facilitate the entering and leaving of the carrier shank to and from the slot in passing from one gear to the other on its way through the serpentine raceway.

With these and other objects in view, the invention consists of certain novel features of construction, as will be more fully described, and particularly pointed out in the appended claims.

In the accompanying drawings:

Figure 1 is a side elevation partly in section illustrating the upper and lower raceway plates with the driving gears set intermediate said plates to engage portions of said carrier to drive the same.

Figure 2 is a fragmental top view showing portions of the top plate with its modified form of raceway formed therein also showing in dotted lines the serpentine raceway in the lower plate and illustrating the action of the driving gears in passing the carrier from the slot in one gear to that in the next for the purpose of driving the carrier through the raceways.

Figure 3 is a perspective view showing a fragmental portion of both the upper and lower raceway plates with a portion of the carrier mounted therein.

Figure 4 is a perspective view showing the guide shoe of the carrier which runs in the upper raceway.

Figure 5 is a top view of the guide shoe and its plate which runs in the lower raceway.

Figure 6 is a sectional elevation of the shoe with its plate which runs in the lower raceway.

Figure 7 is a perspective view showing the fragmental portion of the gear which is formed of a pair of superimposed plates, each being peripherally slotted and provided with teeth and these plates are connected together so that their respective slots will register and their respective teeth will be in staggered relation relatively to each other, a tooth in each opposite plate serving as a flaring guide on the opposite side walls of the slots.

Figure 8 is a plan view showing segmental portions of a pair of gears with their staggered teeth intermeshing and their slots registering.

Figure 9 is a side elevation of the lower portion of the carrier partly in section showing the anti-friction roll sleeve on its shank 28.

It is found in practice in the operation of braiding machines in order to obtain a high degree of speed, of advantage to reduce the extent of the in and out motions of the carrier relatively to the braiding center which in the old style machines the raceway is caused by following the serpentine or figure 8 form of raceway. To obviate this detrimental effect, I have pro-

vided a machine with upper and lower raceways set out of vertical alignment with each other, the upper raceway running much nearer to a true circle than the lower raceway, and the carrier being constructed with an offset portion and arranged to engage both the upper and lower raceways whereby when revolved about a common braiding center the carrier is caused to receive an oscillating motion to swing its yarn guiding eye in and out towards and from the center to compensate in a measure for the opposite movements of the body of the carrier, whereby the guide eye for the thread

will run in substantially a circle thus requiring but a slight movement of the yarn take-up in the carrier; and the following is a detailed description of one construction of mechanism by which these advantageous results may be obtained:

With reference to the drawings, 10 designates the base-plate of my improved braiding machine in which is formed the lower raceway 11 which is in the usual figure 8 form, and this plate is provided with side walls 12 forming a chamber 13 in which the driving gears, presently described, are mounted. On these side walls 13 is mounted 15 the upper raceway plate 14 which is provided with raceways 15 arranged to run with but a slight offset on either side of a circle passing through the centers of the quoits 16.

In order to provide a carrier which is 20 supported and controlled in its action by the operation of these upper and lower raceways 11 and 15, I have formed a weight or tension standard 17 on which both the bottom and top weights 18 and 19 slide and 25 on the upper end of each standard is formed a yarn guide eye 20, the yarn package being carried on the spindle 21 which is supported on the laterally-extending, lower arm 22. On the lower end of this weight standard, 30 I have formed a bearing portion 23 which extends through and oscillates in a hole 24 in the shoe 25.

This shoe is adapted to run and be guided in the upper raceway 15; the lower end 35 of this bearing member 23 extends through and is fixed in an arm 26 in the lower portion of the carrier by a pin 27 or it may be otherwise fixed therein. The arm has an under bearing portion 46^a that rests on the 40 upper surface of the driving gear.

The opposite end of this arm 26 is connected to an elongated, vertical bearing shank portion 28 of the carrier preferably having an anti-friction roll or outer shell 45 28^a which extends through the driving gears and the lower end of this shank is provided with a bearing 29 in the shoe member 30, which shoe has an elongated projection 31 arranged to run in the lower raceway 11. 50 The upper portion of this shoe-member is in disk form being recessed as at 32 to carry a supply of oil which lubricates its seat through the hole and a disk-plate 33 is provided on the shank portion 28 to bear 55 against the under side of the driving gear to support the carrier shank in upright position.

In order to provide means for driving 60 this carrier through its upper and lower raceways, I have formed a train of gears 34, each gear being preferably constructed of a pair of disks and each having teeth 35 and 36 cut on its periphery, and also being slotted as at 37 at intervals about its 65 circumference.

These two disks are then set and permanently connected together so that their slots 37 will register with each other and their teeth 35 and 36 will be in staggered relation to each other, as best illustrated in 70 Figure 7.

When so arranged the tooth 38 on the upper portion of the gear serves as an extension of the side wall 39 of the slot 37, and the tooth 40 on the lower portion of the 75 gear serves as an extension of the opposite side wall 41 of the slot 37 whereby these teeth 38 and 40 cooperate to form guiding horns on the gear to assist in receiving and transferring the portion 28 of the carrier 80 from one gear to another in its travel about the raceway.

The lower member of each gear is provided with a hub 42 which rests upon the lower quoit 43 and through this gear extends a bearing stud 44, the lower end of which is secured by a nut 45 on the threaded extension 46, while the upper end of this stud 85 serve to support the quoit 16 in the upper raceway.

It will be observed that the gears thus formed serve as an elongated bearing for the shank portion 28 of the carrier. It will also be observed that by forming the gears 90 of two separate disks and positioning these disks so as to cause the teeth 35 and 36 to bear a relatively staggering relation, three important results are obtained: first, the

gears may be slotted vertically to receive the shank portion 28 of the carrier and provide an elongated bearing therefor; second, the natural formation of the teeth serves to provide a flaring opening into the slot 37; and third, by so positioning these teeth but a single tooth of each of the gear disks is 95 removed and then by staggering these teeth so little of the stock between the teeth is removed that the intermeshing teeth of the adjacent gears are held when in mesh against any back lashing of lost motion at 100 their slotted meeting edges when opposite the slots thereby causing these gears to run smoothly and without noise which is not possible with any other construction of gears in which a portion of the teeth is removed.

In other words, in operating a high speed braiding machine of this character, it is necessary in order to reduce the wear and tear of the mechanism to the minimum to prevent any back lash or lost motion between the 110 teeth of the driving gears, and in order to produce this effect and permit a portion of the carrier to pass down through the gears to engage both upper and lower raceways, it is necessary that the teeth of the 115 gears be staggered as above described.

In the operation of my improved braiding machine the lower portion of the carrier below the upper raceway plate 14 is caused to follow the serpentine path of the lower 120

raceway 11 while that portion of the carrier engaging the shoe 25 is caused to follow the raceway 15.

Now as the lower portion moves in and out towards and from the center a greater distance than the upper portion controlled by the shoe 25, the lower portion naturally swings the yarn package standard which is mounted on the offset arm 22 back and forth in unison with the swinging movement of the lower portion of the carrier, while the weight standard 17 rotates on its pivotal point 23 in the shoe 25. The oscillating movement of this weight standard necessarily causes its eye-member 20 out through which the yarn 47 is led, to oscillate back and forth in directions which are opposite to the in and out movements of the shoe member 25 owing to the fact that this eye is on the opposite side of the vertical center line through the standard, thus this eye counteracts in a measure the in and out movements of the weight standard and serves to carry the lead eye of the yarn in nearly a circular line through the centers of the upper quoits thereby reducing to the minimum the necessary take-up movement of the yarn take-up weight 18 or other device employed for that purpose.

30 It is found of advantage in braiding machines of this character to provide a stop motion for arresting the action of the machine when the thread breaks or runs out, and to do this in a simple and effective way, 35 I have mounted a disk 42 on the hollow, upright shaft 43 through which the braiding core 46 passes and which extends down through the center of the machine to operate upon the driving mechanism in any of 40 the usual ways (not shown). This disk plate 42 is provided with peripheral projections 44 arranged to engage the horns 45 on the weight 18 when the latter drops due to breakage or running out of the thread. It 45 will be noted that these engaging projections 44 on the stop disk extend into the path of the carrier only when it is traveling through the straight portion of the raceway at which time the offset or shank portion 28 is being revolved or carried in the 50 arc of a circle by its gear about the weight standard 17 and at which time the weight with its knock off horns 45 are traveling at a greatly reduced speed which is the logical time to engage the stop motion as at that 55 time the shock of contact is reduced to the minimum.

60 My improved braiding machine is simple and practical in construction and by its use great braiding speed is obtained.

The foregoing description is directed solely towards the construction illustrated, but I desire it to be understood that I reserve the privilege of resorting to all of the mechanical changes to which the device is sus-

ceptible, the invention being defined and limited only by the terms of the appended claims.

I claim:

1. In a braiding machine, spaced upper and lower fixed raceway plates, the raceway in said lower plate being of a depth less than the thickness of said plate, a carrier guided in and extending through said upper plate and having its lower end guided in the raceway of said lower plate, and a train of driving gears intermeshing with each other and operatively mounted intermediate the raceways for driving said carrier. 70

2. In a braiding machine spaced upper and lower raceway plates having raceways of different contours, a carrier having guide portions to run in both raceways, and a train of driving gears intermeshing with each other intermediate said plates for driving said carrier in said raceways whereby it is caused to oscillate as it travels. 80

3. In a braiding machine, spaced upper and lower fixed plates having raceways therein, the raceway in the lower plate having a closing bottom wall to form an oil-tight raceway groove, a carrier guided in the raceways of both of said plates, a train of driving gears intermeshing with each other and mounted intermediate said plates, 90 and provided with means for engaging a portion of said carrier intermediate the raceways for driving the same. 95

4. In a braiding machine, spaced upper and lower fixed plates having raceways therein, the raceway in the lower plate having a closing bottom wall to form an oil-tight raceway groove, a carrier guided in the raceways of both of said plates, a carrier driving gear operatively mounted intermediate said plates toothed to intermesh with adjacent gears and slotted to engage a portion of the carrier, the teeth of the gear providing entrance guides for the opposite side walls of said driving slot. 100 105

5. In a braiding machine having spaced-apart upper and lower raceways, a carrier guided in both of said raceways, a set of twin gears having staggered gear teeth and operatively mounted intermediate said raceways for driving the carrier, said gears being slotted to engage a portion of the carrier, the intermeshing staggered teeth of the gears cooperating to provide entrance guides for the opposite side walls of said driving slot. 115 120

6. In a braiding machine, upper and lower raceways, a carrier having guide members for each raceway arranged out of vertical alignment with each other, and driving gears intermeshing with each other located intermediate said raceways and also arranged to engage and drive said carrier. 125

7. In a braiding machine having spaced upper and lower raceways, a carrier guided 130

in both of said raceways, a set of rotating gears intermeshing with each other and operatively mounted intermediate said raceways and slotted to receive and drive said carrier, the teeth of said gears adjacent said slots being staggered arranged to prevent lost motion where the carrier is engaged therewith.

8. In a braiding machine, a traveling carrier having an offset gear engaging shank portion, a carrier driving gear having two sets of peripheral teeth arranged in staggered relation and slotted to receive said offset portion, the intermeshing teeth of each gear providing entrance guides to said slots on both of its opposite side walls.

9. In a braiding machine having spaced-apart upper and lower raceways, a traveling oscillating carrier having a portion arranged to engage the upper raceway, and an offset portion arranged to engage the lower raceway, a set of driving gears intermeshing with each other and mounted intermediate said raceways said gears being also slotted to engage and drive said carrier.

10. In a braiding machine having spaced-apart upper and lower raceways, a traveling oscillating carrier having a portion arranged to engage the upper raceway and an offset portion arranged to engage the lower raceway, a train of intermeshing driving gears mounted intermediate said raceways, each of said gears being slotted to engage and drive the carrier, and the intermeshing teeth of the gear at the entrance of its slot providing flaring entrance guides therewith.

11. In a braiding machine having spaced-apart upper and lower raceways, an oscillating carrier having a portion arranged to engage the upper raceway and an offset portion arranged to engage the lower raceway, a set of twin gears with staggered gear teeth mounted intermediate said raceways, said gears being slotted to engage and drive the carrier and the staggered inter-

meshing teeth of each gear at the entrance of its slot cooperating to provide flaring entrance guides thereto.

12. In a braiding machine having spaced-apart upper and lower raceways, an oscillating carrier having a portion arranged to engage the upper raceway and an offset portion arranged to engage the lower raceway, a set of driving gears mounted intermediate said raceways, each of said gears having two rows of staggered teeth, and each gear being slotted to receive said offset portion of the carrier to drive it and the different sets of the staggered teeth providing entrance guides for the opposite walls of said driving slot.

13. In a braiding machine having spaced upper and lower raceways, a travelling oscillating carrier having a portion arranged to engage the upper raceway and an offset portion arranged to engage the lower raceway, a train of driving gears mounted intermediate said raceways, each of said gears having two rows of staggered teeth, each gear being slotted to receive said offset portion of the carrier to drive it and the different sets of the staggered teeth providing entrance guides for the opposite walls of said driving slot, and said staggered teeth cooperating to engage each other the upper tooth on one side of the slot and the lower tooth on the opposite side thereof to prevent lost motion at the slots where the carriers pass through the gears.

14. In a braiding machine spaced upper and lower raceway plates, a carrier guided in the raceways of both of said plates, a set of rotating gears intermeshing with each other and operatively mounted intermediate said plates for driving said carrier, and said carrier being provided with an anti-friction bearing surface on that portion engaged by said gears.

In testimony whereof I affix my signature.
GEORGE F. McCAYEY.
